UNITED STATES PATENT OFFICE.

WILLIAM J. BAUMBERGER, OF DAVENPORT, IOWA, ASSIGNOR, BY MEANS ASSIGNMENTS, TO MICRO MACHINE COMPANY, OF BETTENDORF, IOWA, A CORPORATION OF IOWA.

GRINDING MACHINE.

Application filed June 8, 1922. Serial No. 566,741.

This invention relates to improvements in grinding machines, and more particularly a grinding machine of the vertical type wherein the grinding wheel operates with a vertical movement and the table is given an orbital motion in a horizontal plane to thereby effect grinding of cylindrical surfaces.

One object of my invention is to provide a grinding machine of the character indicated in which provision is made for a wide range of adjustment for grinding the surfaces of cylindrical bodies without the necessity of changing the size of the grinding wheel.

15 A further object of the invention is to provide a grinding machine of the character indicated wherein the grinding wheel operates in a vertical direction and is so mounted as to accommodate any desired range in the 20 depth of the surface to be ground.

Other and further objects of my invention are: to provide a grinding machine wherein the table and the grinding wheel are given movements independently of each other to 25 thereby obtain independent adjustment and variations in the speed of movement of the table; to provide a machine wherein the number of parts is reduced to a minimum to thereby eliminate lost motion and reduce cost 30 of manufacture; to provide a grinding machine wherein the feed mechanism for the table is susceptible of micrometer adjustment; to provide a machine in which the object to be ground may be readily and conveniently mounted and accurately centered 35 with respect to the grinding wheel without throwing off the power; and to provide a machine in which a continuous supply of water may be delivered to the surface being 40 ground to thereby maintain the surface at a proper temperature.

With the foregoing objects in view, as well as others which will be apparent as the description proceeds, the invention consists in the parts and combinations thereof herein-after set forth and claimed, with the understanding that the size, proportion and arrangement may be varied without departing from the spirit and scope of the invention.

45 In the drawings forming a part of this specification, Figure 1 is a side elevation of a grinding machine showing my improvements embodied therein and illustrating the construction which I now prefer. Figure 2 50 is a front elevation of the machine illus-

trated in Figure 1. Figure 3 is a top plan view of the entire machine. Figures 4 and 5 are enlarged vertical sectional views, Figure 4 corresponding to the section line 4-4 of Figure 5 and Figure 5 corresponding to the section line 5-5 of Figure 3. Figure 6 is an enlarged horizontal sectional view corresponding to the line 6-6 of Figure 5. Figure 7 is a detail, vertical, sectional view corresponding to the line 7-7 of Figure 8. Figure 8 is a view in elevation of certain portions of the adjusting feed and drive mechanism. Fig. 9 is a horizontal section on line 9-9 of Fig. 7.

In said drawings, 1 indicates the main base or bed of the machine and 2 a column extending upwardly. The base is rigidly secured to the column as by means of bolts 5 (see Figure 1), the base and column being held in proper alignment as by rib 3 and groove 4 (see Figures 4 and 6). The column 2 is provided at the top thereof with an overhanging arm or cap 6, the same preferably being secured to the column 2 by bolts 7. Secured at its top to the extending arm or cap 6, as by bolts 9, is a head stock column 8, the lower end of said head stock column being secured to the lower portion of the column 2, as best shown in Figure 1. An auxiliary column or guide post 11 is also secured at its top, as by a nut 15, to the extended arm 6 and, at its lower end, is attached by a screw or bolt 13 to the outer bossed portion of a bracket 12 which in turn is rigidly secured to the column 2 as by bolts 14.

The head stock or slidable cross head is indicated at 10 (see Figure 1) and is adapted for vertical sliding movement on the head stock column 8 and auxiliary column 11. At its outer end, said head stock is formed with a spindle clamp housing 10^a suitably bored to receive the upper spindle housing 16 which is removably secured therein as by means of the clamp screws 10^b. Said housing 10^a is vertically slotted as indicated at 10^c to thereby provide for the necessary clamping action when the clamp screws are tightened. A lower spindle housing 17 is removably secured within the housing 16 as by a tapered shank or other suitable means. The grinding wheel spindle 18 is rotatably journaled within said housings 16 and 17 and is provided at its lower end with a grinding wheel 19, the latter being made detachable by any suitable means and interchangeable with 110

other grinding wheels of any desired size. Said spindle 18 is directly driven by a spline shaft 20 to which it is connected by a coupling 21. Said lower spindle housing 17 is 5 provided at its top with a funnel-shaped receptacle 52 adapted to receive water supplied from a hose 53 adapted to move up and down in unison with the head stock, said receptacle 52 having a suitable opening 10 therein to allow the water to flow continuously to the grinding wheel. By employing the auxiliary column 11, it will be noted that I insure a true and perfect vertical motion to the head stock 10, 15 with its attached grinding wheel and maintain its alinement with the base of the machine.

An electric driving motor for the spindle is preferably supported upon an offset 2^a 20 formed as an integral part of the column 2 and in which offset is formed a cylindrical recess 24 in which is mounted for vertical reciprocation, a plunger 23 attached to the bottom of the motor. A coil spring 25 is 25 mounted within the column 2 and is so associated with the plunger 23 as to provide for an automatic adjustment of the tension on the belt operated by said motor. Said motor 22 is provided on its armature shaft with a 30 driving pulley 27 that transmits power to the grinding wheel through belt 26 which passes over idlers 28 to variable speed pulleys 31 and 31^a mounted upon the upper end of said spline shaft 20.

35 To obtain the vertical reciprocation of the head stock 10, I preferably provide the following arrangement. Mounted within the column 2 is a pump 32 arranged to supply hydraulic pressure through a pipe 33 to a 40 control valve 34 also secured to the column 2 (see Figures 1, 2 and 3). By means of said control valve, the hydraulic pressure thus obtained may be distributed to either the top or bottom portion of a cylinder 37 45 mounted in said column 2 and within which is disposed a piston 37^a. The hydraulic pressure is communicated to the upper portion of said cylinder on top of the piston 37^a through a pipe 35 to thereby cause a 50 downward movement of said piston. When it is desired to move the piston upwardly, the pressure is directed through a pipe 36 to the lower end of the cylinder 37 beneath said piston 37^a. The valve 34 is operated by 55 means of a valve lever 48 attached thereto, said lever 48 projecting toward the front side of the machine, as shown best in Figures 1 and 2.

Rigidly connected to the piston 37^a and 60 extending downwardly therefrom, is a piston rod 38 which is rigidly connected at its lower end to a head stock rod 39 as by means of the connector 40, shown in Figure 1. The rod 39, adjacent its upper end, is 65 bolted or otherwise rigidly secured to the

head stock 10, as indicated at 42. At its extreme upper end, said rod 39 is formed with a hook 39^a to which is attached one end of a cable 41 that passes over a pulley 44 rotatably secured in a bracket 45 at the top of the machine. The other end of the cable 41 has a counterbalance weight 43 attached thereto of sufficient size to properly counterbalance the weight of the head stock 10 and movable parts associated therewith. 75

To automatically control the up and down movements of the head stock 10, I preferably employ the following arrangement. Secured to the head stock 10 is a stop rod 51 (see Figures 1 and 2). Adjustably mounted 80 on said rod 51 are stops 49 and 50 each having an outwardly projecting arm, as best shown in Figure 2, adapted to engage and trip the valve lever 48 alternately in accordance with the up and down movements of 85 the head stock. Obviously, the stops 49 and 50 can be so adjusted on the rod 51 as to insure reciprocation of the grinding wheel not only the proper amount vertically but between the proper points. Additional safety 90 end fixed stops 46 and 47 are also used to trip the valve lever in the event the adjustable stops are misadjusted or not properly set.

In order to provide for a circulatory or 95 planetary movement of the article to be ground, as for instance, a gas engine cylinder 150 shown in dotted lines in Figure 1, I preferably employ the following arrangement, it being understood that said circulatory or orbital movement takes place in a horizontal plane or plane perpendicular to the axis of the grinding wheel. Rotatably journaled in the frame of the machine is a horizontally disposed shaft 55 adapted to be 100 rotated by means of the pulley 54 secured at its outer end and driven from any suitable outside source of power. The speed of rotation of the shaft 55 and consequent speed of the orbital movement of the table and 105 work, is preferably regulated by a suitable combination change-speed gearing and clutch indicated conventionally at 57 in Figure 1, said gearing being controlled by a lever 58 working within a quadrant 59 attached to the outer face of the frame. The other end of the shaft 55 (see Figures 1, 7 and 8), is connected by a universal joint or coupling 55^a to a worm jack shaft 55^b having a worm 55^c formed integrally therewith. 110 Cooperable with the worm 55^c is a worm gear 60^a which is mounted within the housing 64, as best shown in Figure 7. Said housing 64 provides a bearing for the end 115 of said jack shaft 55^b and also serves as an oil reservoir to insure proper lubrication for the worm and worm gear. The worm gear 60^a has integral or rigid therewith, a vertically disposed tubular driving shaft 60 120 which is journaled within a bearing 65 in 125

130

turn mounted within a second housing 61. The latter is rigidly secured, as by bolts 63, to a supporting shelf 62 provided within the base 1 (see Figures 1 and 7). The bearing 65 has tapered engagement with the housing 61 to facilitate assembling and dismantling of the parts and is normally held in operative position by means of adjusting nut 66 engaging the lower threaded portions 61^a of the housing 61 and attached to the bearing 65 by a resilient ring or washer 61^b. The lower end of said driving shaft 60 is formed with gibs or dovetailed projections 67 extending horizontally and with which 15 is adjustably engaged a correspondingly dovetailed portion of a plate 68. The latter is provided with an integral or rigid depending stud or pin 69 threaded at its lower end as shown in Figures 7 and 8 and which 20 pin or stud partakes of the nature of a wrist pin, as hereinafter described. In Figures 7 and 8, the parts are shown so adjusted that said stud or wrist pin 69 is axially alined with the drive shaft 60 so that it will be evident, as said drive shaft 60 is rotated, said 25 pin or stud 69 will merely rotate about its own axis and without any eccentric action. Referring more particularly to Figures 4, 5 and 6, it will be noted that I have provided a motion-transmitting element or yoke 30 70, the latter being apertured at its center to receive said stud or wrist pin 69, the latter being held in operative engagement with the yoke 70 as by means of a nut 71 applied to the lower threaded end of said stud. Said yoke 70 is provided with oppositely extending arms, each having an enlargement or bearing 90 suitably transversely bored for the reception of a bushing 91, the latter having sliding engagement with a pair of cross bars 92 which in turn are rigidly connected at their ends by longitudinally extending bars 93. The rigidly connected bars 92 and 40 93 form a unitary structure or rectangular frame which is adapted for longitudinal movement or reciprocation within rigidly supported guides 94 (see Figures 4 and 6) and it will also be observed from an inspection of Figure 4, that said frame may slide 45 vertically with respect to said guides 94. The guides 94 are preferably of angular cross section and rigidly secured to a shelf or support 95 within the base 1 as by bolts 96. The extreme ends of the motion-transmitting yoke 70 are formed with sockets 70^a in which are received the ball ends 70^b provided at the lower ends of a pair of motion equalizer levers 72 and 73 (see Figures 4 and 5). In order to impart circulatory or 50 orbital movement to the main table 83, said equalizer levers 72 and 73 are provided intermediate their ends with ball journals 74 and 75 respectively housed within spherical socket bearings 76 and 77 mounted on a supporting shelf 62. The upper ends of said 55 equalizer levers 72 and 73 are formed with studs or spindles 72^a and 73^a respectively, which slidably engage balls 79 and 80, the latter having ball and socket engagement with bearings 81 and 82 rigidly secured to the under side of said main orbital table 83. All of the bearings 81, 82, 70^a, 76 and 77 are provided with V-shaped apertures (see Figures 4 and 5) to provide the necessary clearance for the oscillating movements of the 60 75 equalizer levers 72 and 73.

Referring to Figures 4 and 5, it will be noted that the main orbital table 83 is slidably supported on horizontally extending bearing surfaces 1^a—1^a provided at the top of the base 1, said bearing surfaces 1^a having suitable oil grooves, as shown in Figure 4, and the table 83 having a depending flange around its periphery. The table 83 is provided with a longitudinally extending rib of dovetail cross section as shown in Figure 4 and with which cooperates a correspondingly dovetailed recess 84^a on the under side of a secondary or supertable 84. By this arrangement, the supertable 84 is adjustable lengthwise of the main orbital table 83 as by the adjusting screw 85 to thereby facilitate centering of the work with respect to the grinding wheel. On its upper face, said supertable 84 is provided with a plurality of transversely extending T slots 86 of well known form and by which are attached longitudinally extending clamping bars 89, the latter being adjusted relatively toward and from each other by a pair of adjusting screws (see Figures 3 and 4).

As hereinbefore explained, when the stud or wrist pin 69 is axially alined with the drive shaft 60 and as shown in Figures 7 and 8, said stud or pin 69 will rotate about its own axis and consequently no movement will be imparted to the motion-transmitting yoke 70. In order to impart movement to said yoke 70 and consequently to the work-supporting table through the intermediary of the yoke, rectangular frame 92—93 and equalizer levers 72 and 73, it is necessary to move the stud or pin 69 to a position eccentric or out of alinement with the axis of the drive shaft 60 and for this purpose, I have provided the following arrangement.

Mounted at the front of the base 1 is a regulating hand wheel 99 secured to a regulating or adjusting gear shaft 100, said gear shaft being provided with a micrometer reading disc 98, as shown in Figure 4. The inner end of the adjusting gear shaft 100 (see Figure 8) is provided with a bevel gear 101 meshing with a bevel gear 102 secured to a vertically disposed adjusting screw 103 (see Figure 7). Said screw 103 is supported for rotation in a portion of the housing 61 and is held in vertical position by said gear 102 and a thrust collar 104 attached to the lower end thereof. The upper portion of 100 105 110 115 120 125 130

the adjusting screw 103 is threaded to engage correspondingly threaded sleeve or nut 105 having a horizontally extended arm and collar portion 106 in which is contained a 5 thrust bearing 107. The thrust bearing 107 is held in position by and secured between a flange of a screw 108 and a flange on the upper end of a vertically extending intermediate adjusting screw 111. As best shown 10 in Figure 9, the upper portion 110 of said screw 111 is squared or of other non-circular cross section to thereby provide a driven connection with a bearing member 112 into which said screw 111 is fitted, said bearing 15 member 112 being threaded to the upper end of the driven shaft 60 to in turn provide a positive driving connection with said shaft.

The screw 111 is formed with a steep pitch 20 thread, preferably about 45°, the threads engaging a corresponding internally threaded upper portion of the vertically disposed nut or sleeve 114 rotatably mounted within the shaft 60 and held in proper position by suitable means such as the thrust bearings 25 115—116. The lower portion of said nut or sleeve 114 is machined to provide a depending stud 117 projecting through the bottom end of the drive shaft 60 to thereby provide a rigid connection with a bevel gear 118 (see 30 Figure 7). As shown in said figure and also in Figure 8, said gear 118 meshes with a bevel gear 122 rigid with a horizontally disposed adjusting screw 121. The screw 121 cooperates with a threaded nut section rigid 35 with the wrist pin plate 68 so that, upon rotation of said screw 121, said plate 68 carrying the stud or wrist pin 69, will obviously be adjusted laterally or radially with respect to the axis of the drive shaft 40 60. Attached to the plate 68 is an adjustable nut 120 (see Figure 8) and secured to bear against the stationary end of plate 68, is a stop 124, acting as a limiting stop to insure the plate 68 with its stud 69 being 45 brought to rest at its neutral or inoperative position so far as imparting planetary motion to the table is concerned.

As has heretofore been explained, when 50 the stud or wrist pin 69 is axially aligned with the drive shaft 60, transmission of power from the shaft 55 does not induce any movement of the work table and consequently the work on the table may be properly positioned and centered with respect to the grinding 55 wheel without throwing off the power. When it is desired to obtain the orbital or circulatory movement of the table and work clamped thereon, the hand wheel 99 is turned to the right, as viewed in Figure 2, thus rotating the adjusting gear shaft 100 and through the latter, bevel gears 101 and 102, and adjusting screw 103. The governor sleeve or nut 105 is thus caused to be moved upwardly, as viewed in Figure 7. Such upward 60 movement of the governor nut or

sleeve 105 elevates the intermediate screw 111 which in turn, due to the steep pitch of the threads thereon, produces rotation of the nut or sleeve 114. Rotation of the nut or sleeve 114 produces rotation of the bevel gear 118 and the latter in turn produces rotation of the gear 122 and consequently of the final adjusting screw or worm 121. The latter causes the plate 68 with its stud or wrist pin 69 to be moved off center and obviously the extent to which said stud is moved off center or the radius of its eccentric motion, can be accurately determined by manipulation of the hand wheel 99. As soon as the stud or wrist pin 69 is shifted to an off center position, it is evident that the power transmitted through the drive shaft 60 and derived from the shaft 55, will induce an orbital or circulatory motion of the yoke 70, which in turn induces a movement of the equalizer 72 and 73 through a path corresponding to the surfaces of cones and this movement is in turn imparted to the main table, thus producing the desired orbital movement of the table and work mounted thereon.

I claim:

1. Mechanism of the character described, including a work table; and means for imparting orbital motion to said table, said means including a driving member, a motion-transmitting member, operative connection with said driving member and motion-transmitting member arranged to impart circulatory motion to said motion-transmitting member, and equalizer, motion-transmitting elements between said motion-transmitting member and said table.

2. Mechanism of the character set forth, including a work table; and means for imparting orbital movement to said table, comprising equalizer levers pivotally mounted intermediate their ends and operatively connected with said table at one set of their ends, a yoke operatively connected to the opposite set of ends of said levers, a frame adapted for reciprocation in one direction and upon which said yoke is movable in a direction transverse thereof, a drive shaft, and operative connections between said drive shaft and said yoke arranged to impart circulatory motion to said yoke.

3. Mechanism of the character set forth, including a work table; and means for imparting orbital movement to said table comprising, equalizer levers pivotally mounted intermediate their ends and operatively connected with said table at one set of their ends, a yoke operatively connected to the opposite set of ends of said levers, a frame adapted for reciprocation in one direction and upon which said yoke is movable in a direction transverse thereof, a drive shaft, and operative connections between said drive shaft and said yoke arranged to impart circulatory motion to said yoke, said connec-

tions comprising a wrist pin in operative relation with said yoke, the wrist pin being adjustable radially with respect to the axis about which it is rotated.

5 4. Mechanism of the character set forth, including a work table; and means for imparting orbital movement to said table, comprising a drive shaft, a second shaft driven thereby, the second shaft rotating about an 10 axis perpendicular to the table, a radially adjustable wrist pin carried by said second shaft, a yoke actuated by said wrist pin, a

frame movable in a plane parallel to and lengthwise of said table, said yoke being mounted on said frame and movable transversely thereof, and equalizer levers pivotally mounted intermediate their ends and operatively connected at one set of ends with said yoke and at the other set of ends with the table.

In witness that I claim the foregoing I have hereunto subscribed my name this 17th day of May 1922.

WILLIAM J. BAUMBERGER.
